UNITED STATES PATENT OFFICE

2,499,893

VALVE DEVICE

George R. Wallen and Herbert R. Trausneck, New York, N. Y., assignors to Anemostat Corporation of America, New York, N. Y., a corporation of Delaware

Application November 4, 1944, Serial No. 562,027

1 Claim. (Cl. 137—139)

1

This invention relates to nozzles, particularly for directing heated air over window surfaces to remove frost and ice therefrom and to prevent the formation of frost and ice thereon, and has for its general object to provide, for this and analogous purposes, a simple, practical nozzle which is specially adapted for disposition with respect to a window or other surface to direct a layer of heated air substantially uniformly over an extensive area thereof so as to accomplish its purpose expeditiously and efficiently.

Other and more specific objects of the invention are: to provide a nozzle embodying simple, practical valve means to control discharge of air therefrom; to provide simple practical means to direct the discharged air against the window or other surface with which the nozzle is associated; and to provide simple, practical means for effecting intermixture of atmospheric air with the heated air in order to reduce the temperature of the heated air in certain instances.

With the foregoing and other objects in view, which will become more fully apparent as the nature of the invention is better understood, the same consists in a nozzle embodying the novel features of construction, combination and arrangement of parts as will be hereinafter more fully described, illustrated in the accompanying drawings and defined in the appended claim.

In the accompanying drawings, wherein like characters of reference denote corresponding parts in related views:

Fig. 1 is a central, vertical, longitudinal section through a nozzle constructed in accordance with the invention; and

Fig. 2 is a section on the line 2—2 of Fig. 1.

Referring to the drawings in detail, it will be observed that the present nozzle comprises a tubular element 10 which is closed at its front end, open at its rear end for supply of heated air thereto, and provided in its side wall, adjacent to its closed front end, with an arcuate slot 11 for discharge of heated air fan-wise laterally therefrom. Thus, said element 10 is adapted to extend transversely across a window framing and to have its closed front end disposed adjacent to a window surface so that heated air discharged through the slot 11 will be directed fan-wise over the window surface. In this connection, the element 10 may be of a length to extend across a window framing of any width to permit the closed front end of said element and, consequently, the slot 11 to be disposed more or less closely adjacent to the window surface. Moreover, the open rear end of said element 10 may be connected in any suitable manner with a source of supply of heated air. Preferably, however, this connection, at least adjacent to said element 10, is disposed at right angles, or at substantially right angles, to said element so as to

extend laterally from the window and thus not occupy space directly in line with the window.

The element 10 may be mounted in any suitable manner at any desired location relative to a window at, of course, the inner side thereof. Preferably, however, it is mounted either at the bottom or at one side of the window, although it may be mounted at the top thereof if desired. In any event, it is mounted with its slot 11 disposed to direct the discharged air over substantially all, or the desired portion, of the window surface. Moreover, the element 10 may be of any desired shape in cross section and the slot 11 may be of any desired width and length. Preferably, however, the element 10 is of circular shape in cross section and the slot 11 is of approximately 180° in length so that the fan-like layer of air discharged therethrough is directed over substantially the entire window surface, assuming, of course, disposition of the nozzle at the bottom, or at one side, or even at the top of the window, as aforesaid.

While the open rear end of the element 10 may be connected in any suitable manner with a source of supply of heated air, it is preferred to provide, as a part of the nozzle, a hollow air supply head 12 to serve both as a support for said element 10 and as a housing for valve means for controlling discharge of air through the slot 11. In this connection it will be observed that the head 12 is of flat, peripherally rounded form at one end and develops toward its other end into a cylindrical neck 13 for connection with an air supply duct. It will further be observed that the element 10 is joined at its open rear end to the front of the head 12 near the first mentioned end of the latter and is disposed at right angles to said head; also, that the front wall 14 of said head to which the open rear end of said element 10 is joined, is provided with an opening 15 in alignment with said element to afford communication between the latter and said head. In addition, it will be observed that the slot 11 is in the side of the element 10 remote from the air inlet end of the head 12. Accordingly, the head 12 serves not only as a support and mounting means for the element 10 and as a housing for valve means to control the air flow, but also as a practical means of extending the air supply laterally from a window with which the nozzle 10 may be operatively associated.

The wall 16 which closes the front end of the element 10 is of conical form and flares forwardly relative to said element. It will be apparent, therefore, that air flowing forwardly through the element 10 will be deflected by said wall 16 forwardly through the slot 11 against a window surface with respect to which the nozzle is operatively disposed. It will also be apparent that this

forward deflection of the air will be uniform throughout the length or angular extent of the slot 11 due to the conical form of the wall 16 and the cylindrical form of the element 11. As previously indicated, however, it is not essential that the element 10 be of cylindrical form. On the contrary, only the portion of said element which is annularly coextensive or substantially coextensive with said slot need be of cylindrical or substantially cylindrical form. Likewise, only the portion of the wall 16 or its equivalent which is annularly coextensive or substantially coextensive with said slot need be of conical or substantially conical form. Moreover, the equivalent of the wall 16 obviously may be provided by an element separate and distinct from said wall as, for example, by a block or the like inserted in the front end portion of the element and having its rear end of conical or substantially conical form.

A valve in the form of a disk 29 is provided for controlling discharge of air through the slot 11. This disk is of a size to cover the opening 15 and is disposed in the head 12, being pivotally mounted, as indicated at 30, upon the front wall 14 of said head at a point approximately in line with a point midway between the ends of the slot 11. It is swingable between a closed position in which it is disposed against the wall 14 of the head 12 in covering relationship to the opening 15, as shown by full lines in Fig. 1, and an open position in which it extends at an angle to said wall 14, as shown by dotted lines in Fig. 1, so as to assist in deflecting the supplied air forwardly through the slot 11 against a window surface disposed in front of said slot.

Any suitable means may be provided for actuating the disk 29 to open and closed positions to control discharge of air through the slot 11. In the present instance snap action means is provided for actuating said disk to its fully open and its fully closed positions. This means comprises a lever 31 pivoted intermediate its ends, as indicated at 32, upon the rear wall 20 of the head 12 and having its forward end disposed in said head and its rear end disposed rearwardly of said head. Carried by the rear end of said lever is a handle 33 for effecting rocking movements thereof, while connecting the front end thereof with the disk 29 is a link 34, the arrangement being such, as shown, that by rocking said lever in one direction said disk is swung toward its open position and by rocking said lever in the other direction said disk is swung toward its closed position. Pivoted to the free end portion of the disk 29 is a rod 35, while fixed within the head 12 beyond the free end portion of said disk is a cross bar 36 having therein, at a point approximately midway between the front and the rear walls of said head, a guide opening 37 through which the rod 35 extends. In addition, a compressed coil spring 38 surrounds said rod 35 between the cross bar 36 and the pivotal connection of said rod with said disk and, by its constant tendency to expand, reacts from said cross bar to swing said disk to either its closed or its open position, depending upon whether said disk is disposed either forwardly or rearwardly of a plane including the opening 37 and the pivot 30 of said disk. The lever 31 is effective to swing said disk from either its closed or its open position to a position beyond the said plane and thereafter the spring 38 obviously acts to effect completion of the opening or closing movement of said disk with a snap action.

4
A division of the present application, Serial No. 635,855, was filed on December 19, 1945, and has matured into Patent No. 2,434,340, dated January 13, 1948.

5 From the foregoing description considered in connection with the accompanying drawings it is believed that the construction and mode of operation of the present nozzle will be readily understood and its advantages appreciated. It is desired to point out, however, that while only certain specific embodiments of said nozzle have been illustrated and described the same is readily capable of various other specific embodiments within the spirit and scope of the invention as defined in the appended claim.

10 We claim:

15 A device of the character described comprising a hollow head having in its bottom an air inlet opening, said head including front and rear walls in the former of which is an air outlet opening, a valve plate in said head pivoted at its top to the front wall of said head adjacent to the top of said air outlet opening for swinging movement between open and closed positions relative to said air outlet opening, a member fixed in said head below said valve plate and having a guide opening therein, a rod pivoted to a lower part of said valve plate and extending loosely through said guide opening, a coil spring surrounding said rod 20 above said member and tending constantly to react from the latter to urge said rod upwardly, whereby it operates to effect either opening or closing movement of said valve plate depending upon whether the pivotal connection of said rod 25 with said valve plate is disposed forwardly or rearwardly of a plane including the pivotal connection of said valve plate with said front wall and the guide opening in said member, and means for initiating opening and closing swinging movements of said valve plate from closed and open 30 positions thereof, respectively, comprising a lever pivoted to the rear wall of said head and having a link connection with said valve plate.
